UNITED STATES PATENT OFFICE.

ALBERT W. PEARSALL, OF LOWELL, MASSACHUSETTS, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

No. 873,590.

Specification of Letters Patent.

Patented Dec. 10, 1907.

Application filed November 8, 1905. Serial No. 286,339.

To all whom it may concern:

Be it known that I, ALBERT W. PEARSALL, of Lowell, in the county of Middlesex and State of Massachusetts, have invented certain new and useful Improvements in Pneumatic-Despatch-Tube Apparatus, of which the following is a specification.

My invention relates to improvements in pneumatic despatch tube apparatus and relates especially to an inlet for despatching carriers through said apparatus at an intermediate point between the open end of the tube and the receiving station without the use of other means than the simple pressing of the carrier against the valve. This inlet is so arranged as to permit of its operation when the propelling force is either atmospheric pressure or a pressure created within the system, and has the advantage over the invention shown in Letters Patent #669485 dated March 5, 1901 issued to me, in that carriers despatched from a point remote from the inlet are permitted to pass through said inlet without interruption; and has a further advantage in the fact that the inlet valve is held closed by means of a spring instead of using a complicated and finely adjusted cylinder and piston valve; another advantage is that the tension of said spring may be adjusted and graduated with reference to the propelling force used in the particular line in which it is inserted. In former devices of this character a fixed force has been imparted to the valve through which the carriers are introduced by having pneumatically operated force exerted against the introduction or inlet valve and it frequently occurs in actual practice that the force required to open the inlet valve is excessive. By the use of the inlet herein described the actuating pressure on the inlet valve may be varied by increasing or decreasing the tension on the spring operating the valve.

Another object of this invention is to provide against leakage around the valve at the inlet by means of a flexible seat for said valve, which seat slightly projects into the inlet passage so as not to interfere with the introduction of the carrier but sufficiently to expose a lip or edge to the atmosphere, which lip is forced firmly against the surface of the valve by the atmospheric pressure.

In the accompanying drawings which illus-

trate a construction embodying my invention, Figure 1 shows a general arrangement of a circuit of pneumatic tubes in which my improved type of inlet is shown and through which a carrier is being despatched upward at a point intermediate an ordinary inlet and a receiving terminal. Fig. 2 is a sectional view of Fig. 1. Fig. 3 is an enlarged vertical sectional view of the automatic inlet showing a carrier being introduced and the open position of the valve shown by dotted lines. Fig. 4 is a detail view of the adjustment segment and tension spring. Fig. 5 is a front elevation of parts shown in Fig. 4.

Like letters of reference refer to like parts throughout the several views.

In the general view (Fig. 1) the atmospheric pressure is admitted in the bell mouth A and is drawn through the tube B and through the terminal C connected thereto in the direction indicated by the arrows, thence through the ordinary inlet D which is connected to the transmission tube E in which automatic inlet F is inserted. The tube E then connects with the receiving terminal G, through which the air passes into the ordinary despatch inlet H, and through the transit tube I into the downward receiving terminal J. The air after being drawn through the downward receiving terminal J is conducted through the tube K which is connected to the source of power. Carriers ejected from the terminal J are received in the receiving shelf L.

The improved inlet shown in detail (Fig. 3) consists of the outer case F and the introduction plate F'. The gasket F² consists preferably of rubber or some similar flexible material, and is clamped between the case F and plate F' and projects into the inlet opening. This forms a flexible seat for the valve F³ which is pivoted at F⁴ to the case F. On the valve F³ is pivoted by the pin F⁵ the lever F⁶ which is bifurcated at its upper end and which is operated and guided within the slot F⁷ in the lever F⁸ by means of a pin fixed in said lever F⁶. The upper extremity of the lever F⁷ is rigidly attached to the tension pin F⁹, which pin is pivoted in the case F. The tension pin F⁹ (Fig. 4) carries the slot F¹⁰ on its outer end and in which one end of the helical spring F¹¹ is inserted. The other end of the spring F¹¹ is fixed in adjustable position by graduating pins F¹² inserted in a seg-

mental plate fixed on the case F. The cotter pin F¹² holds the spring F¹¹ in position on said tension pin F⁹.

To despatch a carrier through the inlet F, 5 the carrier X, (see Fig. 3) is pressed by the operator against the valve F³ which causes said valve F³ to open inwardly against the tension of spring F¹¹ until it assumes the position shown in dotted lines. The influx of 10 air through the opening in the inlet F drives the carrier into the regular circuit in transmission tube E, thence into the terminal G from whence it is discharged. After the carrier X passes the valve F³ said valve is closed 15 by the tension of spring F¹¹ preventing a further influx of air.

Having thus described my invention and set forth a construction embodying the same, what I claim as new and desire to secure by Letters Patent of the United States is:

1. In a pneumatic despatch tube apparatus, an inlet having an opening for despatching carriers, a valve adapted to open inwardly and controlling said opening, spring actuated means for holding said valve normally closed, and means for regulating the tension of said spring actuated means.
2. In a pneumatic despatch tube apparatus, an inlet having an opening for despatching carriers, a pivoted valve adapted to open inwardly and controlling said opening, a

lever pivoted to said valve, a pin mounted on the free end of said lever, a lever pivoted to the case at one end and having a slot at the other end adapted to guide and actuate said pin, and a spring adapted to apply tension to said slotted lever.

3. In a pneumatic despatch tube apparatus, an inlet having an opening for despatching carriers, a valve adapted to open inwardly for controlling said opening and normally closed, flexible means located at said opening actuated by atmospheric pressure against the face of said valve when normally 45 closed for preventing leakage thereby.

4. In a pneumatic despatch tube apparatus, an inlet having an opening for despatching carriers, a valve adapted to open inwardly for controlling said opening and normally closed, a flexible gasket fixed to said inlet forming a seat for said valve and projecting slightly into said opening, said gasket being held by atmospheric pressure against the face of said valve when normally 55 closed for preventing leakage thereby.

In testimony whereof, I have signed my name to this specification in the presence of two subscribing witnesses, this first day of November A. D. 1905.

ALBERT W. PEARSALL.
